Henry Dreyfuss, South Pasadena, Calif., assignor to
Bell Telephone Laboratories, Incorporated, Berkeley
Heights, N.J., a corporation of New York

Filed July 3, 1967, Ser. No. 7,680

Term of patent 14 years

(Cl. D26—14)

FIG. 1 is a bottom perspective view of a telephone handset showing my new design;

FIG. 2 is a top perspective view of the telephone handset shown in FIG. 1;

FIG. 3 is a top plan view of the telephone handset shown in FIGS. 1 and 2;

FIG. 4 is a side elevational view of the telephone handset shown in FIGS. 1 and 2;

FIG. 5 is a side elevational view partially broken away and partially in cross section of the receiver portion of the telephone handset shown in FIG. 4; and

FIG. 6 is a fragmentary side elevation of a modified embodiment of the receiver portion shown in FIG. 1, it is understood that the handle member is identical in both embodiments disclosed on the drawing.

The telephone handset cord shown in broken lines in FIGS. 1 and 2 is for illustrative purposes only.

I claim:

The ornamental design for a telephone handset, substantially as shown and described.
